Primary Examiner — Ian Simmons*Assistant Examiner* — Keith Wilson(74) *Attorney, Agent, or Firm* — Fish & Richardson P.C.(57) **CLAIM**

The ornamental design for an oven cabinet, as shown and described.

DESCRIPTION

FIG. 1 is a perspective view of an oven cabinet.

FIG. 2 is a front view of the oven cabinet of FIG. 1.

FIG. 3 is a back view of the oven cabinet of FIG. 1.

FIG. 4 is a left side view of the oven cabinet of FIG. 1.

FIG. 5 is a right side view of the oven cabinet of FIG. 1.

FIG. 6 is a top view of the oven cabinet of FIG. 1.

FIG. 7 is a bottom view of the oven cabinet of FIG. 1.

FIG. 8 is an illustration of the oven cabinet of FIG. 1 as part of a first exemplary outdoor kitchen; and,

FIG. 9 is an illustration of the oven cabinet of FIG. 1 as part of a second exemplary outdoor kitchen.

The broken lines depict environment and form no part of the claimed design. Shade lines are not an indication of surface texture or gloss.
